UNITED STATES PATENT OFFICE

126,968

DESIGN FOR AN ADVERTISING SIGN

Gertrude I. Shepherd, Portland, Oreg.

Application January 6, 1941, Serial No. 97,831

Term of patent 7 years

To all whom it may concern:

Be it known that I, Gertrude I. Shepherd, a citizen of the United States, residing at Portland, in the county of Multnomah and State of Oregon, have invented a new, original, and ornamental Design for an Advertising Sign, of which the following is a specification, reference being had to the accompanying drawing, forming part thereof.

I claim:

The ornamental design for an advertising sign, as shown.

GERTRUDE I. SHEPHERD.
